UNITED STATES PATENT OFFICE.

WADE W. MOORE, OF PITTSBURG, CALIFORNIA, ASSIGNOR TO JESSE E. ROACH, OF OAKLAND, CALIFORNIA.

LEAD-PENCIL.

1,382,928.

Specification of Letters Patent. Patented June 28, 1921.

Application filed February 17, 1920. Serial No. 359,469.

To all whom it may concern:

Be it known that I, WADE W. MOORE, a citizen of the United States, residing in the city of Pittsburg, in the county of Contra Costa and State of California, have invented a new and useful Improvement in Lead-Pencils, of which the following is a specification.

My invention relates to improvements in lead pencils of the type wherein a permanent body is supplied with extra leads, wherein a tip portion, having a coaxial bore and magazine therein operates in conjunction with a body portion having means for projecting a lead through said tip portion.

The primary object of the present invention is to provide an improved simplified and economical construction having an increased efficiency.

20 A further object of the present invention is to provide a new and improved construction, for pencils of the character described, adapted to facilitate the transmission of a new or extra lead from the magazine to the writing tip of the pencil.

25 A still further object of the invention is to provide a new and improved construction easily, economically and readily assembled to reduce the cost of parts and the manufacture of the pencil.

30 Another object of the improvement is to provide an improved construction having greater stability and fewer operations both in the production and operation of the pencil.

35 I accomplish these several objects by means of the improved device disclosed in the drawings forming a part of the present specification wherein like characters of reference are used to designate similar parts throughout the specification and drawings, and in which—

40 Figure 1 is an enlarged broken longitudinal sectional view of my improved pencil; Figs. 2, 3 and 4 are further transverse sectional views taken on lines 2—2, 3—3 and 4—4, respectively, of Fig. 1, in the directions indicated;

45 Fig. 5 is an enlarged broken view, partly in vertical longitudinal section, of the body portion only of the pencil;

50 Fig. 6 is an enlarged elevation of the tip portion only;

Fig. 7 is a top plan view of Fig. 6; and Fig. 8 is a further enlarged transverse sectional view taken on line 8—8 of Fig. 1 in the direction indicated. 55

Referring to the drawings the numeral 1 is used to designate in general the tip portion of the pencil which comprises a tubular 60 cylindrical portion 2 and a hollow tapered portion 3. The writing tip of the tapered portion 3 is provided with an axial bore 4 having a threaded portion 6, the purpose of which will hereinafter be more fully set 65 forth.

The cylindrical portion 2 of the tip portion 1 is knurled or otherwise roughened as at 7 in order to facilitate retention of the pencil in the head during the writing 70 process.

75 Into the threaded portion 6 of the tapered portion 4 is screwed one end of a coaxial tube 8 which is held in spaced relation with the cylindrical portion 2 of the tip portion 1 by means of a washer or partition 9 sweated or otherwise secured within said tip portion 1 at the junction, preferably, of the tapered and cylindrical portions 3 and 2 respectively, and bored centrally to engage 80 and retain said tube 8 as disclosed in Fig. 1 of the drawings.

85 The spaced relation of the axial bore or tube 8 to the tip 1 provides an annular magazine 16 between said tube 8 and the internal walls of the cylindrical portion 2 of the tip portion 1, within which magazine may be stored additional or extra leads 14.

90 The tube 8 is recessed or slotted longitudinally as at 11 to permit the frictional engagement of a spring clamp 12, mounted upon said tube 8, between the partition 9 and writing point, with a lead 14 within tube 8 or axial bore of the tip portion 1 to normally prevent longitudinal movement of 95 said lead 14 within said axial bore.

99 The upper end of the magazine 16 is open and substantially flush with the upper end of the cylindrical portion 2 of the tip portion 1 of the lead pencil. The upper end 100 of said portion 1 is provided with a reduced externally threaded portion 21 which is arranged to be engaged by the internally threaded lower end of a tubular body portion 22 to close said magazine 16 and said 105 body portion is provided with means to

project a lead through the axial bore 4 of the tip portion 1 in the following manner:

The body portion 22 is provided near its lower end with a bearing 23 within which is 5 rotatably mounted the lower end of a hollow cylindrical externally threaded rod 24 having a radially disposed longitudinal slot 26 therein and a cylindrical member 27 secured in axial alinement to the opposite or upper 10 end of the rod 24, said member 27 being provided with an annular flange 28 to rotatably engage the annular recess or shoulder 29 in the adjacent or upper end of the tubular body portion 22 and thereby center the 15 upper end of the rod 24 with said body portion 22 and at the same time provide a bearing for the upper end of said rod 24.

The member 27 may be provided with a chamber 30 within which is secured an 20 eraser 32 by means of a screw 33, the upper end of the member 27 with eraser 32 being inclosed by means of a suitable ornamental cap 34 in threaded engagement with the upper end of member 27 as disclosed in Fig. 25 1 of the drawings.

The opposite or lower end of the rod 24 is provided with an externally threaded portion 36 which extends beyond or below said bearing 23 and is engaged by a nut 37 having 30 diametrically opposed holes or apertures 38 for the reception of a spanner or other wrench or tool to screw or unscrew the said nut 37 upon the rod 24, and thereby move the flange 28 of the member 27 down onto the 35 annular recess 29 of the tubular body portion 22, thereby effectively, securely and rotatably securing the threaded rod 24 within the body portion 22.

A threaded follower 41 is mounted upon 40 the threaded rod 24 and is provided with projecting teeth 42 on one side thereof to slidably engage a plurality of longitudinally disposed internal grooves 43 within the body portion 22.

The follower 41 is also provided with an 45 internal annular groove 44 which is slidably engaged by a T-headed lateral extension 46 of a plunger 47 slidably mounted within the radially disposed longitudinal slot 26 of the 50 threaded rod 24, said plunger 47 being arranged substantially coaxial with the body portion 22 and with the tube 8 whereby longitudinal movement of said plunger 47 will move the same into the coaxial bore or tube 55 8 of the tip portion 1 of the pencil.

The lateral extension 46 of the plunger 47 is slidably connected with the groove 44 of the follower 41 so that when the rod 24 is rotated the radial slot 26 thereof will, 60 of course engage the lateral extension 46 of said plunger 47 and rotate the same while the follower 41 will not rotate being non-rotatably but longitudinally slidably connected, through the medium of the teeth 42 and grooves 43, with the body portion 22.

The member 27 and ornamental knob 34 provide a means exteriorly of the body portion 22 whereby the plunger actuating mechanism may be operated.

In operation the body portion 22 is held rigid and the knob 34 or member 27 is rotated which will in turn rotate the threaded rod 24 and cause the same to move the slidably mounted follower 41 longitudinally within the body portion 22 of the pencil and thereby actuate the plunger 47 to move into the axial bore of the tip portion 1 and project a lead within said bore beyond the end of the writing point of the pencil, the spring clamp 12 meanwhile frictionally engaging the lead to normally prevent movement thereof within said bore.

This frictional engagement is provided to prevent loss of the lead within the bore when the pencil is inverted.

The novel construction readily facilitates the renewal of a lead within the writing point by elimination of processes now necessary in similar pencils heretofore on the market.

In the present instance it is only necessary to unscrew the body portion 22 from the tip portion 1 and the magazine 16 with its extra leads 14 is readily and instantly accessible. A lead is removed from the annular magazine 16 and placed in the adjacent or upper end of the bore or tube 8 of the tip portion 1 and the body portion 22 is then screwed back onto the said tip portion 1 which operation will close the magazine 10 to prevent accidental or inadvertent removal of the remaining leads therefrom.

By operating the knob 34 or member 27 as hereinbefore described said renewed lead will be projected through the coaxial bore 105 or tube 8 of the tip portion 1.

In constructing this new and novel pencil it is only necessary to screw the tube 8 into the threaded portion 6 of the tip portion 1 and seat the partition or washer 9 therein 110 to center said tube.

In the body portion 22 it is only necessary to secure the member 27 to the rod 24 by means of solder or the like, after the eraser retaining screw has been positioned, and then mount rod 24 within the bearing 23 and screw and tighten the nut 37 on the threaded end of said rod 24. Said rod 24 will then be securely and rotatably mounted within the body portion 22 and need not be removed for replenishing or other than repair purposes.

The simplicity and economy as well as stability of construction presents a novel arrangement by means of which the process of renewing a lead or projecting one from the coaxial bore of the pencil is greatly facilitated.

The simplified construction also permits of an economical assembling of the various 130

parts and a permanent stability of the finished product.

Having thus described my invention what I claim as new and desire to secure by Letters Patent is—

1. In a lead pencil, the combination with a tip portion having a coaxial bore and an annular magazine surrounding said bore, of a tubular body portion having one end thereof for engagement with the tip portion to close the magazine therein and likewise having a bearing adjacent said end; a threaded rod having a longitudinally disposed radial slot therein having its inner end rotatably mounted within said bearing and having a threaded end extending beyond said bearing, the other end of said rod having a bearing on the opposite end of the tubular body portion to retain said rod coaxial longitudinally with said body and to provide exteriorly located means for the operation of said rod; a threaded follower mounted upon the rod and slidably engaging the tubular body portion and having an annular internal groove therein whereby said follower may be moved longitudinally when the rod is rotated; a plunger slidably mounted within the radial longitudinal slot of the threaded rod and the coaxial bore of the tip portion and having a lateral extension on one end thereof to slidably engage the annular slot within the follower whereby said plunger may be actuated to project a lead through the axial bore of the tip when the threaded rod is rotated; and a nut screwed upon the threaded end of the rod extending beyond the bearing within the body portion to prevent longitudinal movement of and to rotatably secure said rod within said body portion; and means for frictionally engaging said lead to prevent longitudinal movement thereof within said bore.
2. In a lead pencil, the combination with a tip portion having a coaxial bore and an annular magazine surrounding said bore, of a tubular body portion having one end thereof arranged for engagement with the tip portion to close the magazine therein and likewise having a bearing adjacent said end; a threaded rod having a longitudinally disposed radial slot therein having its inner end rotatably mounted within said bearing and having a threaded end extending beyond said bearing, the other end of said rod having a bearing on the opposite end of the tubular body portion to retain said rod coaxial longitudinally with said body and to provide exteriorly located means for the operation of said rod; a threaded follower mounted upon the rod and slidably engaging the tubular body portion and having an annular internal groove therein whereby said follower may be moved longitudinally when the rod is rotated; and a plunger slidably mounted within the radial longitudinal slot of the threaded rod and the coaxial bore of the tip portion and having a lateral extension on one end thereof to slidably engage the annular slot within the follower whereby said plunger may be actuated to project a lead through the axial bore of the tip when the threaded rod is rotated; and a nut screwed upon the threaded end of the rod extending beyond the bearing within the body portion to prevent longitudinal movement of and to rotatably secure said rod within said body portion.
3. In a lead pencil, the combination with a tip portion having a coaxial bore and an annular magazine surrounding said bore, of a tubular body portion having one end thereof arranged for engagement with the tip portion to close the magazine therein and likewise having a bearing adjacent said end; a threaded rod having a longitudinally disposed radial slot therein having its inner end rotatably mounted within said bearing and having a threaded end extending beyond the bearing, the other end of said rod having a bearing on the opposite end of the tubular body portion to retain said rod coaxial longitudinally with said body and to provide exteriorly located means for the operation of said rod; a threaded follower mounted upon the rod and slidably engaging the tubular body portion and having an annular internal groove therein whereby said follower may be moved longitudinally when the rod is rotated; and a plunger slidably mounted within the radial longitudinal slot of the threaded rod and the coaxial bore of the tip portion and having a lateral extension on one end thereof to slidably engage the annular slot within the follower whereby said plunger may be actuated to project a lead through the tip when the threaded rod is rotated; a nut screwed upon the threaded end of the rod extending beyond the bearing within the body portion to prevent longitudinal movement of and to rotatably secure said rod within said body portion; and a clamp arranged for frictional engagement with said lead to normally prevent movement thereof within said bore.

In witness whereof I hereunto set my signature,

WADE W. MOORE.
